UNITED STATES PATENT OFFICE

JULIUS D. LIPPMANN, OF EAST ORANGE, NEW JERSEY, ASSIGNOR TO TEXTILEATHER CORPORATION, OF NEWARK, NEW JERSEY, A CORPORATION OF NEW JERSEY

TANDEM COATING MACHINE

Application filed May 19, 1928. Serial No. 278,957.

This invention relates to the coating of a strip of textile fabric for the purpose of producing substitute leather and the like. The object of the invention broadly is to reduce the cost of production of multicoated fabrics of this type. The invention is particularly applicable to a continuous process of coating.

Heretofore it has been the usual practice to drag a strip of fabric by a wind-up roll at the end of the apparatus first through a coating machine and then through a drying room after which the fabric has been customarily rolled up on a spindle, carried back to the coater, and again threaded through the coater and the drying room to receive a second coat. In practice a triple-coated finished product has required three passages through the same machine or, if the machine were arranged, three similar parts one after the other, it has required operators for each of the three parts making up the machine. If it should be attempted alternately to coat and to dry a fabric by dragging it from the far end through all the coating machines and all the drying chambers, too severe a tension stretch would be applied to the fabric, resulting in tearing and damage to the coated surface and often to the fabric itself.

In carrying out my present invention, although I have preserved the continuity of the strip being coated through several coating and drying units, I do not rely upon a dragging force at the end of the set of units to do any more than take up the slack from the last unit, but on the other hand provide dragging propulsion means within each drying unit. I also provide such means as are operable to propel the fabric solely by engagement with the uncoated surface thereof. In addition, I provide means quickly to effect the drying of each coating on the surface of the fabric before it becomes necessary for this coated surface to contact with a guiding roller. This initial drying objectively must be carried beyond the tacky point, while additional drying of the coating may be effected in the drying layout before the application of another coat of coating dope to the fabric.

Objectively I provide for the application

of a plurality of coats, preferably three or more, at the same time at different localities to a strip of fabric which when finished is a multicoated fabric.

A further object of my invention is to provide for speed coordination between the several propelling means for the fabric strip to accommodate for the stretch of the fabric in its traverse through the apparatus. 55

It is a further object to combine with this provision to compensate for the stretching of the fabric a safety means which permits a certain amount of uncommensurate traverse of the strip being coated through the various coating units of my apparatus. 60

A further object of the invention is to provide improved means operated positively for drying a coated fabric and for accomplishing this purpose within economical space. 65

It is a further object of my invention to improve in general and in combination and in details of construction an apparatus for coating, drying and winding up a multicoated strip of fabric in a continuous manner. 70

The above and further aspects of my invention will be set forth more particularly in the accompanying claims, which are directed to an illustrative embodiment of my invention described in the following specification in connection with the accompanying drawings which form a part hereof. The claims are directed to this illustrative embodiment solely for purposes of illustration and not limitation. 75

In the drawings, Fig. 1 is a two-sheet diagrammatic layout in side elevation partly in vertical section of a triple tandem coater constructed in accordance with my invention; Fig. 2 is a plan view of the layout shown in Fig. 1 drawn to a reduced scale; Fig. 3 is a cross-section taken through the plane of line III—III of Fig. 1; Fig. 4 is an enlarged longitudinal section through the drying hood at the locality of the removable part; Fig. 5 is a perspective disassembled view, parts being broken away of the hood construction with particular reference to the removable curved part; and Fig. 6 is a detailed cross-section with parts broken away 85

and parts shown in elevation of the distal end of the drying hood.

Three complete operating units, A, B and C are illustrated, completing the tandem coater. Each unit comprises a coater 1 and a dryer 2. The invention, however, comprises more than the mere arrangement of these three units A, B and C in series with a fabric strip D to be coated passing there-through. According to ordinary practice a stock roll 3 of the fabric D might be provided at the proximal end of the apparatus and a wind-up roll 4 of this fabric D at the distal end of the apparatus. Such rolls are illustrated in this embodiment, but they are totally incapable of carrying through the functioning desired. Sufficient power applied to the wind-up roll 4 to drag the fabric D through the three coating machines and three drying rooms would result in tearing the fabric strip in two somewhere between the winding roll 4 and the entrance to second unit. If it were conceivable that the fabric strip could stand the dragging stress at the distal end of the apparatus sufficient to draw the entire strip through the three units, it would without doubt crinkle it and become corrugated by the stretch and distorted out of all semblance to that of the desired finished product.

On the contrary, in connection with the practice of my invention within each drying unit 2 is provided a driving or propulsion card roll E power-driven by a suitable propulsion mechanism to impart to it a peripheral speed commensurate with the desired linear traverse of the fabric strip D at that particular locality, while the wind-up roll 4 at the distal end of the apparatus is constantly over-driven through friction means to take up the final slack of the finished fabric strip, but not so as to exert a driving force of any appreciable amount upon the fabric strip; in fact not to exert any dragging movement upon the strip back of the last card roll E. For example, the card roll E of unit A engages solely the uncoated undersurface of the fabric strip D and operates upon the bight F of fabric D which encircles the card roll E, one ply 5 of which extends forth from the guiding roll 6 to the card roll F and another ply 7 of which extends back to the guiding roll 8. Within the drying apparatus additional guide rolls 9, 10, 11, 12 and 13 are provided constraining the fabric strip D to continue in the form of zig-zag laps down to the exit portion 14 which extends up to the second coater 1. A suitable framework 15 may be covered by a gas and heat retaining wall structure 16, 17, 18 and 19, it being preferred that the wall 16 be easily removable. One of the functions of the zig-zag plies between the rolls 9, 10, etc. is to employ gravity 60 acting upon the substantial horizontal runs

to serve as an automatic take-out maintaining a normal tightness for the lap 7 regardless of whether the zig-zag laps vary somewhat in their slackness. This acts as an automatic compensation to take care of any 70 inaccuracy between the propulsion speed imparted to the card roll E and the first unit and to that of the next unit in a distal direction.

Within each drying unit is provided a 75 forced feed drying drum or hollow apron G which envelops the bight F of coated fabric and is provided with exit perforations 21 serving to drag forcible jets of conditioned hot drying gas upon the coated surface of 80 the fabric D. This heated conditioned drying gas is supplied from a pressure main 25, each local supply being controllable by a damper 26 controlling the local flow to each local apron or hood G through a branch 85 duct 27.

The detailed construction of this drying apron G is shown best in Figs. 3, 4, 5 and 6. Fig. 3 shows the mounting of the apron within the drying room frame with the arrows 90 indicating the forced jets of drying gas upon the fabric. Each drying apron comprises three main parts—30, 31 and 32. The runs 30 and 32 are substantially horizontal and are connectable and disconnectable at the 95 right hand ends as shown in Fig. 1 by the curvilinear or cylindrical flue 31 which together with the runs 30 and 32 are formed so as to permit ready and frequent connections and disconnections. Flanges 35 and 36 are formed on the ends of the runs 30 and 32, while symmetrically similar flanges 37 and 38 are formed on the cylindrical duct 31. The ends of the duct 31 telescope over the mouths 40 of the parts 30 and 32 while a 100 pair of clamping cleats 41 and 42 engage the flanges 35 and 37 and 36, 38 respectively detachable to hold the parts together. The assembled relation is shown in Fig. 4 of the disassembled perspective illustrated parts shown in Fig. 5.

The terminal end of this drying hood is fitted with the flange construction adopted to be closed by a flanged terminal cap 45 as shown in Fig. 6. This cap is removable by sliding to facilitate the cleaning of the interior of the apparatus.

The removability of the cylindrical flue 31 is of importance to permit the threading of the fabric strip D about the card roll E and to facilitate the disposition of the bight in fabric F thereabout and also for the purpose of renewing the card cloth on this card roll when such becomes necessary.

The coaters 1 may be of any suitable and usual type, although they are shown comprising doctor blades 50 and local dope reservoirs 51 discharging dope through their spouts 52 directly upon the upper surface of

the fabric D to be distributed by the doctor blades 50.

For the proper propulsion of the fabric through the apparatus illustrated, two commercial variable speed devices known as speeders H and I are provided. These speeders are well known in the art and may be designated as speeders. It is convenient to mount one speeder H upon the drying room frame of intermediate room B and the second speeder I upon the drying room frame on the last unit C. Power is received from the power belt 60 and is passed through on a suitable counter shaft and pulleys and belt 61 to pulley 62, shaft 63, pulleys 64 and 65 by belts 66 and 67 respectively. Speeders I and H, that is, the belts 66 and 67, apply power to the driven end of the speeders. A system of sprocket chains and sprockets 69, 70, 71, 72, 73, 74, 75, 76 and 77 effects simultaneous speed control of both the speeders H and I, so that a hand engagement of the sprocket chain 76 located within reach of the operator attending the coater 1 of a unit is sufficient to control the speed imparted to each of the card rolls E for each of the three units, and likewise to control the wind-up speed for wind-up roll 4.

The application of power from the speeders H and I to the card rolls is effected through a drive pulley 80 fixed to the shaft 81' of each card roll through suitable belts 81, 82 and 83. Speeder H, through the medium of belts 84 and 81, drives the card roll of unit A and also through the medium of belts 85 and 83 operates the card roll of unit C. The speeder I through the medium of belt 86 and belt 82 drives the card roll of the intermediate unit B. The friction wind-up device 90 of wind-up roll 4 is driven through belt 91 and belt 94, extending from the main power shaft without the intermediary of one of the speeders because of the fact that this wind-up roll is always slightly overdriven and strippage is permitted. In the initial set-up of the apparatus the relative sizes of the pulleys employed is such as to provide the desired degree of increased peripheral speed for card roll E of unit B over that of unit A, and for card roll A of unit C over that of unit B to allow for the stretch of the fabric occasioned by the tension thereon and by the effect of the doctor blades. It is also preferable that the sprocket wheel 70 be adjustable on its shaft to permit of relative adjustment in the control of the speeders H and I.

What I claim and desire to secure by United States Letters Patent is:—

1. Tandem apparatus for fabricating coated fabric comprising several longitudinally spaced dope applicators; a drying hood spaced after each dope applicator; means for drawing a strip of textile fabric in tandem through said dope applicators and drying hoods comprising a propulsion roll associated with each

drying hood; and means for simultaneously driving said propulsion rolls at various individual propulsion speeds whereby said fabric as an entirety is propelled throughout its length instead of being dragged solely at its far end; and whereby compensation for stretch in said fabric is provided.

2. In combination two or more dope applicators and two or more drying room layouts for simultaneously multicoating a continuous moving strip of fabric characterized by the fact that a driven card roll engaging solely the uncoated surface of said fabric is provided for each drying room layout and functions to draw said fabric through the preceding coater and through the stage of the drying room in which said coated fabric is tacky and characterized further by the fact that zig-zag traverses within said drying room are provided; between said card roll and the next drawing propulsion means for said fabric strip; adjustable speed power means for driving said card rolls at compensating speeds to take care of the stretch of said moving strip.
